UNITED STATES PATENT OFFICE

GEORGE I. THEILE, OF HAMILTON, OHIO, ASSIGNOR TO THE HOOVEN, OWENS, RENTSCHLER COMPANY, OF HAMILTON, OHIO, A CORPORATION OF OHIO

CONVEYER

Application filed November 9, 1925. Serial No. 67,918.

This invention relates to machinery for the manufacture of sugar, and has to do particularly with the carriers or conveyers by means of which bagasse passes from one set of crushing rolls to another.

One of the principal objects of the invention is to provide adjustable means whereby the inlet end of such a conveyer or carrier may be maintained in predetermined relationship with the upper and lower cooperating juice expressing rolls.

Further objects and advantages of the invention will be apparent, from the description thereof set out below when taken in connection with accompanying drawing.

In the drawing, in which like characters of reference designate like parts throughout the several views thereof,

Fig. 1 is a side elevation, somewhat diagrammatic in character, of two adjacent sets of mill rolls, with a connecting carrier or conveyer having an adjustable inlet end embodying the present invention;

Fig. 2 is an enlarged elevational view of one end of the conveyer, and the cooperating mill rolls, to more clearly show the details of the invention;

Fig. 3 is a fragmentary sectional view just inside of the mill housing looking across the conveyer; and

Fig. 4 is a vertical sectional view of a slightly modified form of construction.

As is well known, the greater part of the world supply of sugar is extracted from sugar cane. In the extraction of the juice in such manufacture of sugar the cane is passed through a succession of sets of heavy rolls under high pressure which squeeze the juice out of the stalks of cane. The resulting squeezed cane which is called bagasse, is passed successively through the various sets of rolls, the expressed juice running down from the rolls and being collected for subsequent treatment. Obviously some means must be provided for moving the bagasse

from one set of rolls to the next and in practice many different forms of conveyers or carriers to effect this transfer of the bagasse have been worked out. One well-known form of conveyer is that shown in the patent to Meinecke, No. 1,401,965 dated December 20, 1921, which comprises generally an inverted V-shaped trough or chute, with its opposite ends positioned in cooperative relation with the two sets of rolls between which the bagasse is to be moved. The invention forming the subject matter hereof has to do primarily with the construction of the inlet end of such a conveyer.

As shown in the drawing the numerals 10 and 11 designate respectively the two sets of rolls, such sets of rolls being generally referred to as "mills" and the rolls thereof generally referred to as "mill rolls," between which the bagasse is to be moved, the cane traveling from the mill 10 to the mill 11. The numeral 12 designates the trough-like conveyer, of inverted V-shape, through which the bagasse is moved from the mill 10 to the mill 11.

As shown particularly in Fig. 2 the mill 10 comprises three mill rolls 15, 16 and 17, the cane or bagasse to be acted on by the mill passing in between the rolls 15 and 16, and thence outwardly through the rolls 16 and 17, in a conventional manner. In order for the conveyer or carrier to operate satisfactorily, means must be provided for directing the bagasse as it flows from between rolls 16 and 17 into the conveyer. To accomplish this there is provided an upper scraper plate 20, having a scraper tip 21 detachably connected thereto and a lower scraper plate 22 having a scraper tip 23 attached thereto. The scraper tip 21 is positioned to cooperate with upper roll 16 to remove the bagasse therefrom and to direct the bagasse into the conveyer or carrier. The scraper tip 23 is positioned to cooperate with lower roll 17, to remove bagasse therefrom and direct it into the carrier. The scraper

plate 20 is rigidly secured, in any desired manner, to the bar 25, which extends substantially parallel to the several axes of rolls 15, 16 and 17, and is of a length corresponding to the length of these rolls. This bar at each end is turned down to be substantially circular in cross section, as shown in dotted lines at 26, these cylindrical ends being fitted within rectangular blocks 27, each block being bored to have a running fit on the cylindrical ends 26. Each of these blocks is slidably mounted within the rectangular slot 28, in the bearing member 29, which bearing member is supported by a plate 30, provided with suitable bolt holes for attachment to any convenient portion of the mill-roll housing. As shown, the plate 30 is preferably provided with elongated slots 31 adapted to receive attaching bolts by means of which arrangement the setting of the plates may be varied to give the generally desired setting of the scraper plates. Mounted upon the bar 25, inside of each of the bearings 29, is a lever or arm 40, preferably extending a substantial distance away from the mill rolls.

Attached to the lower scraper plate 22 is a bar 45, at each end of which is attached a lever or arm 46, of substantially the same size and shape as the upper lever or arm 40. The bar is suitably supported, at opposite ends, in bearing members 47, which are provided with mounting slots similar to arrangement and function to the slots 31 described above. Extending through a suitable opening or passage 50 in each of the levers 40 and 46 is a bolt 51, the upper end of which extends a considerable distance beyond lever 40 and is surrounded by a spring 53. At its extreme upper end the rod 51 is loosely provided with a plate 54 held by an adjusting nut 55 threadedly mounted on the rod, against which one end of the spring 53 bears. The rod is also surrounded by a bearing plate 56, against which the lower end of the spring 53 rests. This plate 56 is also provided with a knife-edge bearing 57, held in contact with the end of the lever 40 by means of the spring.

Attached to the upper scraper plate 20 is a hinged extension 60, the construction being such that as the bagasse passes into the conveyer, this extension 60 will be always held in contact with the top plate of the carrier or chute to thus prevent loss of cane over the top scraper plate.

During operation of the device it is desirable that the scraper tips 21 and 23 shall be maintained at all times in contact with co-operating rolls 16 and 17. The spring 53 tends to move the opposite ends of the levers 40 and 46 toward each other. This causes the scraper tip 23 to rock into contact with roll 17 and at the same time slides the block 27 in the bearing 29, to swing the upper scraper plate 20 about the tip of the scraper tip 21 as a fulcrum, thus insuring proper contact

between the scraper tip 21 and its cooperating roll 16. As the bagasse moves from between the rolls 16 and 17, it will in general be in greater volume than may readily pass between the scraper plates when those plates are in inoperative position. The pressure of the cane on the upper scraper plate 20 therefore causes that plate to move upwardly carrying the bar 25 and the block 27 with it, and pivoting about the scraper tip 21 as a fulcrum. As the scraper moves upward it thus provides increased opening for the passage of cane between the two scraper tips, the upper scraper under such circumstances assuming a position, for illustration, such as shown in dotted lines in Fig. 2. At the same time this causes lever 40 to move away from the lever 46 thus compressing spring 53. As a result there is a constantly increasing resistance to outward movement of the scraper plate 20 and therefore a constantly increased pressure on the mat of cane as the quantity of bagasse increases. Exact position of the scrapers and plates during operation will be determined by the thickness of mat of bagasse and the stiffness of the springs and may be anywhere between the full inmost position, which is shown generally in full lines in Fig. 2 and full outmost position which is shown generally in dotted lines in Fig. 2.

In actual practice the spring 53 would probably be longer and also of larger diameter than is shown on the drawing when used with other parts of the proportions shown, in order to properly take care of the considerable movement of parts that will take place. It is to be borne in mind that the mill rolls 16 and 17 in a large-size standard apparatus would probably have a diameter of 34 to 36 inches and an effective length of about 7 ft. Furthermore the cane as it passes between the rolls 16 and 17 will probably be subjected to a pressure of from 400 to 600 tons. Naturally, as soon as this pressure is released the mat of bagasse commences to expand considerably and the passage between plates 20 and 22 must necessarily be considerably larger than passage between the rolls 16 and 17.

It is evident therefore that there may be considerable movement of plates 20 and 22 with respect to each other. However, the question of proper proportion of these parts is one that must be worked out in connection with each particular installation, inasmuch as rolls of various sizes operating under widely varying conditions are used in practice. The drawing herewith is merely intended to illustrate the general construction and arrangement of the parts, and the exact proportions will have to be worked out to fit the particular needs. However, this is purely a mechanical matter and anyone generally skilled in construction and operation of sugar-mill operation could readily determine suitable sizes and proportions.

During operation the scraper tips 21 and 23 are pressed tightly against their cooperating rolls. Consequently, wear of these tips does not interfere with the proper operation. 5 However, if there should be such excessive wear of the top scraper tip that general readjustment is desired the arrangement of the elongated slots 31 in the plate 30 will permit of accomplishing this. If desired, both tips 10 21 and 23 may be detachably connected to their respective scraper plates so that after they have worn sufficiently to make it desirable they may be readily replaced by new scraper tips. By varying the angle of the 15 slot within which the block 27 slides, any desired final angle between the plates can be secured.

It is not essential that the two levers 40 and 46 shall be connected together by means 20 of the bolt 51. If desired these levers may be completely unconnected. For example, as shown in Fig. 4, a spring 70 may be provided for cooperation with the lever 46 to hold the plate 23 against its cooperating roll; 25 and a spring 71, one end of which rests against any suitable fixed abutment 72, the other end of which bears against the end of the lever 40 may be used in connection with the upper lever 40. The operation of this form of a device would be the same as described above.

While the forms of apparatus herein described constitute preferred embodiments of the invention, it is to be understood that the invention is not limited to these precise forms 25 of apparatus, and that changes may be made in either without departing from the scope of the invention which is defined in the appended claims.

What is claimed is:

49 1. In an intermediate chute for sugar mills and the like; pivotally mounted scraper members, means tending to rotate said scraper members upon their pivot mountings, and means to permit said scraper members to separate under pressure of the material passing between the scraper members themselves.

50 2. In an intermediate chute for sugar mills and the like; scraper members, pivotal mountings therefor, supporting means for said pivotal mountings one of the pivotal mountings being constructed to permit bodily movement of such mounting and of the scraper member supported thereby independently of its associated supporting means, and means for urging said scraper members toward each other.

55 3. In an intermediate chute for sugar mills and the like; scraper members, pivotal mountings therefor, supporting means for said pivotal mountings one of the pivotal mountings being constructed to permit bodily movement of such mounting and the scraper member supported thereby independently of its associated supporting means, and means for urging such scraper members toward each

other and for rotation on their pivotal mountings.

4. In an intermediate chute for sugar mills and the like, comprising a plurality of crushing rolls; pivotally mounted scraper members associated therewith, means tending to rotate said scraper members on their pivots to urge the tip of each scraper member against its cooperating roll, and yielding means for urging the said scraper members toward each other independently of movement of said crushing rolls. 70

5. In an intermediate chute for sugar mills and the like, comprising a plurality of crushing rolls; pivotally mounted scraper members associated with said rolls, one of said scraper members being bodily movable upon its pivotal mounting independently of movement of its associated crushing roll, means tending to rotate the scraper members on their pivots to urge the tip of each scraper member against its cooperating roll, and yielding means for urging the bodily movable scraper member toward the other scraper member. 80

6. In an intermediate chute for sugar mills and the like, comprising a plurality of crushing rolls; upper and lower scraper members, pivotal bearings for each scraper member, and supporting members for said bearings, one of the said bearings comprising means movably mounted on its supporting member. 90

7. In an intermediate chute for sugar mills and the like, comprising a plurality of crushing rolls; upper and lower scraper members, pivotal bearings for each scraper member, and supporting members for said bearings, one bearing comprising a sliding block mounted on its supporting member. 100

8. In an intermediate chute for sugar mills and the like, comprising a plurality of crushing rolls; upper and lower scraper members, pivotal bearings for each scraper member, supporting members for said bearings, one of the said bearings comprising means slidably mounted on its supporting member, and yielding means for resisting sliding movement thereof in one direction. 105

9. In an intermediate chute for sugar mills and the like, comprising a plurality of crushing rolls; upper and lower scraper members, slidable bearing means for supporting said upper scraper member, said bearing means being so mounted as to be independent of movement of the associated crushing roll, and means for urging the slidable bearings and upper scraper member toward the lower scraper member. 115

10. In an intermediate chute for sugar mills and the like, comprising a plurality of crushing rolls; upper and lower scraper members associated with said rolls, bearing means for supporting the upper scraper member constructed to permit bodily movement of said upper scraper member with respect to 125 130

the lower scraper member independently of movement of its associated crushing roll, and means for urging the upper scraper member toward the lower scraper member.

5 11. In an intermediate chute for sugar mills and the like, comprising a plurality of crushing rolls; scraper members associated with said rolls, and bearings for supporting each of said scraper members, the bearings

10 for supporting the upper scraper member comprising a supporting member, a slidable bearing block carried by said supporting member, and means cooperating with the upper scraper member for urging the said sliding block toward the lower scraper member and for moving the upper scraper member about its bearing to bring its tip into contact with its associated roll.

15 12. In an intermediate chute for sugar mills and the like, comprising a plurality of crushing rolls; upper and lower scraper members associated with said rolls, bearings for pivotally supporting the said scraper members, that bearing supporting the upper 20 scraper member comprising a supporting member and a slidable bearing block carried thereby, and means cooperating with the scraper members for urging the sliding block toward the lower scraper member and for 25 rotating both scraper members about their pivotal bearings to bring the tips of the said members into contact with their respective cooperating rolls.

30 13. In an intermediate chute for sugar mills and the like, comprising a plurality of crushing rolls; upper and lower scraper members associated with said rolls, bearings for pivotally supporting the said scraper members, that bearing supporting the upper 35 scraper member comprising a supporting member and a slidable bearing block carried thereby, and means cooperating with the scraper members for urging the sliding block toward the lower scraper member, and for 40 rotating both scraper members about their pivotal bearings to bring the tips of the said members into contact with their respective cooperating rolls, said means comprising arms carried by the scraper members and spring 45 means cooperating with said arms.

50 14. In an intermediate chute for sugar mills and the like; pivotally mounted scraper members, means tending to rotate said scraper members upon their pivot mountings, 55 means to permit said scraper members to separate under pressure of the material passing between the scraper members themselves, and an extension plate pivotally connected to one of the scraper members.

55 15. In an intermediate chute for sugar mills and the like, pivotally mounted scraper members, means tending to rotate said scraper members about their pivotal mountings, supporting means for said pivotal mountings 60 means to permit bodily movement of one of

65 said scraper members away from or toward said other scraper member independently of its supporting means, a chute end associated with said scraper members and adapted to receive bagasse passing therefrom, and an extension plate having a free pivotal connection with said bodily movable scraper member and positioned in feeding relation with said chute end.

70 In testimony whereof I hereto affix my signature.

75 GEORGE I. THEILE.
